Primary Examiner—Mitchell Siegel

(21) Appl. No.: **29/127,549**

(74) Attorney, Agent, or Firm—Eric Karch

(22) Filed: **Aug. 8, 2000**

CLAIM

(51) LOC (7) Cl. **15-03**

The ornamental design for an attachment wheel for a
concrete finishing machine, as shown and described.

(52) U.S. Cl. **D15/28**

DESCRIPTION

(58) Field of Search **D15/28; 404/112,
404/127, 128; 16/18 R, 19, 45-48; 180/19.1;
37/142.5, 379, 410, 444**

FIG. 1 is a perspective view of a attachment wheel for a
concrete finishing machine, showing my new design;
FIG. 2 is a front elevational view thereof;
FIG. 3 is a rear elevational view thereof;
FIG. 4 is a right side elevational view thereof, the left side
elevation view being a mirror image thereof;
FIG. 5 is a top plan view thereof; and,
FIG. 6 is a bottom plan view thereof.
